UNITED STATES PATENT OFFICE.

JOHN SWITZER OWENS, OF LONDON, ENGLAND.

OPEN-FRONT FIREPLACE STOVE FOR BURNING COKE.

Application filed February 3, 1927, Serial No. 165,833, and in Great Britain February 6, 1926.

This invention relates to an open fire place stove for burning coke and it has for its object to provide an open fire place stove in which the front of the fire place stove is the main 5 or only surface radiating heat into the room, no heat being radiated to the room from the top of the fire place stove, thus overcoming the obscuring effect incidental to fire places of ordinary form when fresh fuel is added 10 to the top of the fire, and which fire place stove whilst primarily designed for use with coke will burn anthracite coal, wood or any other fuel or refuse, said fire place stove moreover presenting substantially the appearance 15 of an ordinary domestic fireplace, and possessing high radiant efficiency but being so constructed that the rate of consumption of the fuel shall be capable of being readily controlled so that the same fire place stove 20 may be used for either a large or small room.

With a fire place stove according to the present invention any fumes from the coke or other fuel cannot enter the room and further the lighting may be easily and quickly 25 effected with or without use of wood and paper.

Moreover with a fire place stove according to this invention provision may be made whereby the fuel is automatically supplied, 30 so that the fire will burn for a considerable period without attention.

In a fire place stove according to this invention there is provided a large radiating surface formed by a relatively small amount 35 of fuel, the air for combustion entering the front of the fire place stove, which is the radiating surface, so that a high temperature is maintained at this point. The radiating surface is moreover so disposed as to throw the heat in the most effective direction.

In order that the invention may be the better understood drawings are appended illustrating one form of fire place stove according to this invention as designed for fitting 45 in the ordinary fire place without structural alteration.

Fig. 1 is a front elevation partly in section.

Fig. 2 is a section on line A A Fig. 1.

Fig. 3 is a part sectional plan as seen from 50 the top of the fire place stove.

Fig. 4 is a side elevation.

Fig. 5 is a side view of the movable hood.

Fig. 6 is a section on line B B Fig. 5.

Fig. 7 is a view showing certain details.

Fig. 8 is a sectional view showing certain 55 modifications.

Fig. 9 is a front view of certain of the parts shown in Fig. 8.

Referring to the accompanying drawings 1 indicates the sides of an outer case formed 60 of cast iron, 2 the back and 3 the top of the said case, said top and back cooperating to hold the said sides in the desired spaced relationship. 4 indicates a bar or plate placed at the back of the fireplace and at the 65 bottom thereof and extending between the sides 1, and which may be extended to completely close the bottom of the fire place stove, thus forming a base or bed plate for the fire place stove. The sides 1 are provided, as 70 will hereafter be more fully explained, with lugs or projections for the support of the fire bars and other parts.

a indicates a partition extending between 75 the sides 1 and supported in spaced relationship to the back and top of the case to form a flue a¹, said partition forming the back of the fire box, the front of which is constituted by a grid comprising an upper member 5 and lower member 6 to which are secured 80 respectively the upper and lower ends of the vertically disposed bars or rods 7. The upper end of the grid formed as just described is supported in U shaped lugs or projections 85 formed upon the inner face of the sides 1, whilst the lower end is supported in a channel or trough formed in a tray 8 in its turn supported by projections 8^a also provided upon the inner face of the sides 1, which tray 90 also serves to support the grate 9. It will be noted that the position of the supports for the upper and lower ends of the front grid are so placed that they are not in vertical alignment, the upper ones being upon a plane 95 inside the plane of the lower ones. Consequently the grid inclines towards the front from top to bottom, and any ash that may fall will fall inside the grid and not outside.

The back a of the firebox is also inclined from the top forwards, so that the said space 100 as a whole may be said to incline forwardly and be of gradually diminishing width from top to bottom.

The back of the firebox is formed in part by a grid 10 mounted in an opening at the 105 lower end of partition a and supported at its ends by projections 11 formed on the inner surfaces of the sides 1 and by the partition a. The grid 10 may either be as shown in Figs. 1 to 3 or it may be formed of a number of bars of circular cross-sectional outline upon which are threaded blocks of fire 110

clay or the like *w* of circular or other cross-sectional outline as shown in Fig. 7. The grid 10 is preferably so mounted as to permit of its ready removal when so desired.

6 The partition forms a dead plate indicated by 12, which, as also the sides 1, may be faced with fire-clay or other similar material, said dead plate acting to cut off the draught from the upper part of the fire and to provide a 10 space or magazine for the fuel.

To increase the capacity of the fuel storage space there is provided in the front thereof a plate 13 disposed above the front grid and removably supported at its ends by projections 15 such as 14 formed upon the inner faces of the sides 1.

Disposed at the back of the firebox and behind the grid 10 is a plate or baffle 15 inclined as shown, whereby the passage of ash 20 and dust to the flue is prevented and under which plate the products of combustion pass to the flue and thence to house flue or chimney. The lower edge of the plate 15 is disposed in or substantially in the plane of the 25 fire bars 9, the space between said plate and the grid 10 forming an ash-pit. 17 indicates a removable plate forming part of the fuel space.

The plate 15 at its lower end is inturned 30 as shown at 15^a and is disposed above an ash-pan 18, so that when the said ash-pan is in the closed position a space is left through which the draught may pass to the flue as indicated by the arrows *x*. The ash-pan is 35 of such length that it extends to the back of the case and is provided at the inner end with a portion 18^a which may be vertical as shown, or it may be inclined and which, when the ash-pan is moved, will control the size of the 40 opening to the flue. The ash-pan 18 at its front end is provided with an outwardly and upwardly inclined plate 19 designed to catch any falling cinders, the said ash-pan fitting snugly between the cheeks or sides of 45 the grate and also against the front of the part of the tray 8, whereby the entry of air at these points is as far as possible prevented when the ash-pan is in the closed position. For a similar reason the back of the ash-pan 50 where it enters the flue must fit well all round. In the partly open position air is allowed to by-pass to the flue without passing through the fire.

20 indicates a cover provided upon the out- 55 side with lugs 21 between which engage pins such as 22 Figs. 1 and 2 whereby the said cover may be hingedly mounted upon the sides 1, and which cover may either occupy the position shown in full on Fig. 2, or opened 60 as shown by the dotted lines when it is desired to introduce a fresh charge of fuel into the fuel space.

22^a indicates a catch or fastening whereby when in the position shown in Fig. 2 the 65 opening of the cover is prevented, or if de-

sired the fastening may be turned to permit the cover to be partly opened, the catch then being caused to occupy a position such that it will rest upon the front edge of the top 2 70 whereby the cover may be supported in a partly opened condition to admit air to the flue from the top of the fire. This catch may be fixed upon the front frame instead of on the cover. As shown more clearly in Figs. 5 and 6 the cover is closed at the top or front 75 and comprises two side members 23 and 24, a sheet of metal 25 forming the bottom or back, the said side members being of such cross-sectional outline that there is provided upon the outer faces of each of them a passage or opening 26 communicating with the flue and through which any fumes escaping at the sides of cover may pass.

Between the front and back plates of the 80 cover a permanently open passage is provided communicating with the flue both in the closed and partly open condition. This 85 passage may be adjustable as to opening, such as by means of a butterfly damper 27, Fig. 2, within the cover, so as to by-pass more or less air to the flue above the fire but without such air passing through the fire, thus 90 regulating the quantity passed through the fire from front to back. The cover is preferably 95 fitted in such a way as to be easily removed from its pivots, as shown at 22 in Fig. 2 and 21 in Fig. 5. By this means there is provided a permanent opening through the canopy communicating directly with the flue whereby any fumes rising from the front 100 of the fire are carried off and prevented from entering the room. When the canopy is partly open more air is permitted to pass the chimney without passing through the fire from front to back, thus controlling the 105 draught through the fuel and the back of the grate.

It will be understood from the foregoing 110 description that apart from the permanent opening in the canopy the draught may be caused to enter the chimney in one or all of three ways, that is above the fire as in an ordinary fire place stove; through the front 115 of the fire place and the grid at the back, or under the grate by suitably manipulating the ash-tray. This permits the fire to be lighted in the ordinary way, the cover being adjusted during lighting so that the products of combustion have free access to the 120 chimney under the cover. After the fire has been lighted in this way, the damper which forms part of the cover may if necessary be adjusted and the draught so altered as to cause more air to pass through the fire from front to back.

Instead of lighting the fire in the ordinary 125 way a gas burner of suitable form may be provided for this purpose, which burner may be separated from or incorporated in the grate.

Instead of effecting the adjustment of the size of the opening to the flue by means of the ash-pan, a swinging or sliding damper may be provided for this purpose, and may be fixed either to the casing of the fire or in the ash-pan, and in the former case the ash-pan need not extend to the back of the fire. Whilst the grid at the back of the fire is preferably removable it may, if desired, be fixed.

The fire brick blocks or sections *w* when such are strung upon the bars forming the back of the firebox may be of any suitable dimensions so as to provide openings between 15 of suitable width, and the upper parts of the said bars may be covered by a small block of fire brick or suitable small blocks of such dimensions that there will be no openings between adjacent blocks for about the upper 20 half of the depth of the firebox, thus forcing the draught to pass through the lower part of the back of the firebox. Moreover the small sections of fireclay are less liable to crack and break than larger masses while 25 such parts as may be injured can be easily replaced without requiring a new grid to be provided. For the purpose of permitting the removal of the fire-clay blocks the grid or the bars may be individually removable.

According to the modification shown in Figs. 8 and 9, in place of the back bars formed in one piece as a solid casting, the construction of the back of the fire box may be as shown in which case the upper portion 35 or dead plate of the back of the fire-box is provided with a mass or block of fire-clay 27 having holes or recesses 28 which loosely engage the upper ends of bars 29 of suitable heat resisting material, steel for example. 40 The lower ends of the bars are supported by the tray 8 carrying the fire-bars 9.

The depth of the recesses 28 may be such that the bars may be moved longitudinally to free their lower ends from the tray 8 when 45 they may be readily removed and others substituted, or the lower ends may be freed by removing the bottom tray 8.

Whatever material is used the bars may be so shaped as to present to the fire sloping sides to induce the ash to pass back with the draught and should preferably present no flat surfaces to the fire to hold and prevent the ash and dust passing away between the bars. The back grid is also preferably sloped 50 backwards from below upwards, so that the fuel space is somewhat triangular in section. This arrangement tends to cause the ash to settle on the back grid through which it is carried by the draught.

The ash-pit may be lined with firebrick so as to protect the sides of the outer case as well as to preserve a higher temperature and form a combustion chamber and thus tend to consume or prevent smoke when bituminous 60 coal is used. To assist this an opening may

be provided above the sloping dead plate forming the magazine and communicating with the ash pit or combustion chamber so that any smoke passing upwards from the top of the coal may be drawn through this 70 opening into the combustion chamber, which obviously may be fitted with a suitable boiler for providing hot water and utilizing the waste heat.

Instead of being separate the bottom tray 75 8 may be formed integral with the grid 10.

Instead of providing the cover or hood with a plate such as 25 so arranged that when the cover is closed it will entirely cut off connection with the flue or chimney, the plate 80 may be dispensed with and a damper may be provided independent of the said cover whereby the connection between the fuel space and flue or passage may be closed at the same time leaving a passage to the chimney 85 from the front of the fire. The damper may either be operable by, or part of the hood, or independent thereof, the arrangement being such that when the cover is closed an opening 90 is left sufficient only to prevent the collection of unburnt gases above the fuel in the fuel space.

The cover may be arranged to open upwards or downwards. In the example illustrated it is arranged to open downwards.

Owing to the arrangement by which the draught is caused to enter the front of the fireplace stove certain advantages are gained; notably the radiating surface is kept nearly vertical instead of a large part being horizontal, while the addition of fresh fuel to the top of the fire does not mask the radiating surface as in the ordinary fire place. In addition the front of the grate may be placed flush with the wall and directly under the 100 cover without loss of radiation. This removes the danger of fumes passing into the room and does away with the need for a strong draught through the fuel to prevent any escape of such fumes into the room; such 105 strong draught being often a cause of fusing or burning of the bars. Obviously as applied when building into new houses, the back plate 2 may be omitted, the flue then being 110 formed between the plates 15 and 12 and the 115 usual brick work of the chimney recesses.

Claims:

1. An open front fire place stove including an outer casing, a fuel chamber in said casing, a fire-box in said casing disposed for receiving fuel from said chamber, a back flue extending in said casing at the rear of said chamber and fire-box, a top flue in said casing above said chamber, means for passage of draft from the rear of the fire box to said back flue, means for passage of draft from the front of the fire-box to said top flue, and means for passage of draft from below the fire box to said back flue.

2. An open front fire place stove including

an outer casing, a fuel chamber in said casing, a fire-box in said casing disposed for receiving fuel from said chamber, a back flue extending in said casing at the rear of said chamber and fire-box, a top flue in said casing above said chamber, means for passage of draft from the rear of the fire-box to said back flue, means for passage of draft from the front of the fire-box to said top flue, means for regulating the draft passing by said last mentioned means, and means for passage of draft from below the fire-box to said back flue.

3. An open front fire place stove including an outer casing, a fuel chamber in said casing, a fire-box in said casing disposed for receiving fuel from said chamber, said fire-box embodying a front grid, a back grid and a grate, a back flue extending in said casing at the rear of said chamber and fire-box, a top flue in said casing above said chamber, means for passage of draft from said back grid to said back flue, means for passage of draft to said top flue from the space at the front of the fire place on the front side of said front grid, and means for passage of draft from below said grate to said back flue.

4. An open front fire place stove including an outer casing, a fuel chamber in said casing, a fire-box in said casing below said chamber, said chamber being open at its bottom and said fire-box open at its top and communicating with said chamber for direct passage of fuel therefrom to the fire-box, said fire-box consisting of a front grid, a back grid, a grate and portions of the end walls of said casing, a back flue extending in said casing at the rear of said chamber and fire-box, a top flue in said casing above said chamber, means for passage of draft from said back grid to said back flue, a movable cover constituting closure means for said fuel chamber at its top and providing means for passage of draft to said top flue from the space at the front of the fire place on the front side of said front grid, and a movable ash-pan for providing passage of draft from below said grate to said back flue.

5. An open fire place stove including an outer casing, a fuel chamber in said casing, a fire-box in said casing below said chamber, said chamber being open at its bottom and said fire-box open at its top and communicating with said chamber for direct passage of fuel therefrom to the fire-box, said fire-box consisting of a front grid, a back grid, a grate and portions of the end walls of said casing, a back flue extending in said casing

at the rear of said chamber and fire-box, a top flue in said casing above said chamber, means for passage of draft from said back grid to said back flue, a movable cover constituting closure means for the fuel chamber at its top and providing means for passage of draft to said top flue from the space at the front of the fire place on the front side of said front grid, means in said cover for regulating the draft passing through the cover, and a movable ash pan for providing passage of draft from below said grate to said back flue.

6. An open front fire place stove including, an outer casing, a curved partition in the outer casing forming a fuel space in the upper portion of said casing, a baffle plate extending downwardly from the lower end of said partition, a back flue formed between said partition and baffle plate and the rear side of said casing, a fire-box consisting of a back grid, a front grid, a grate and portions of the end walls of said casing, said fire-box receiving at its upper end fuel from said space, means at the lower end of said baffle plate for passage of draft from said back grid to said back flue, means for passage of draft from below said grate to said back flue, and movable means providing closure for said fuel space at its upper end and passage to said top flue of draft from the space at the open front of the fire place on the front side of the front grid.

7. An open front fire place stove including, an outer casing, a curved partition in the outer casing forming a fuel space in the upper portion of said casing, a baffle plate extending downwardly from the lower end of said partition, a back flue formed between said partition and baffle plate and the rear side of said casing, a fire-box consisting of a back grid, a front grid, a grate and portions of the end walls of said casing, said fire-box receiving at its upper end fuel from said space, means at the lower end of said baffle plate for passage of draft from said back grid to said back flue, a movable ash pan for providing passage of draft from below said grate to said back flue, and a pivotally movable cover for closing said fuel space at its upper end and providing passage to said top flue of draft from the space at the open front of the fire place on the front side of the front grid, said cover having damper means for regulating said draft.

In testimony whereof I have hereunto set my hand.

JOHN SWITZER OWENS.
